J. M. BLYTH

PICTURE FOLDER AND EASEL

Filed Jan. 20, 1927

FIG. 1.

FIG. 2.

FIG. 3.

FIG. 4.

John M. Blyth,
INVENTOR,
BY *P. L. Strichfield*
Donald B. Stewart,
ATTORNEYS.

UNITED STATES PATENT OFFICE.

JOHN M. BLYTH, OF CHICAGO, ILLINOIS, ASSIGNOR TO EASTMAN KODAK COMPANY, OF ROCHESTER, NEW YORK, A CORPORATION OF NEW YORK.

PICTURE FOLDER AND EASEL.

Application filed January 20, 1927. Serial No. 162,282.

This invention relates to picture supports, and particularly to a combined holder and easel for pictures. One object of my invention is to provide a simple picture holder which may be made from a single piece of sheet material by a single punching operation. Another object is to provide a picture holder which will hold a picture securely and which will permit pictures to be changed. Another object is to provide a picture holder in which punched out flaps form the sole picture retaining structure. Still another object is to provide a picture holder in which the picture is supported behind a frame, the picture holding members being concealed from the front of the holder, and other objects will appear hereinafter from the following specification, the novel features being particularly pointed out in the claims at the end thereof.

Coming now to the drawings wherein like reference characters denote like parts throughout:

Fig. 1 is a perspective view of a picture support constructed in accordance with and illustrating one form of my invention;

Fig. 2 is a section on line 2—2 of Fig. 1;

Fig. 3 is a rear plan view of a picture support showing the construction of the picture holding members; and

Fig. 4 is a fragmentary front plan view of a picture support before the flaps are bent into a picture holding position.

In the embodiment illustrated in the drawings the picture support consists of a single piece of sheet material such as tough cardboard of the type commonly used in photographic folders. The entire picture support may be made by punching out the sheet material into the desired shape, the picture holding members being also cut out in the same operation.

As best shown in Fig. 1, there is a picture supporting member 1, which is held at an angle to form an easel by means of flaps 2 bent along the edges 3. A picture 4 is carried in the frame designated broadly as 5.

The frame 5, as best shown in Fig. 4, is formed by cutting the material 6, of which the support is made, along the lines 7 and 8. These intersecting cuts form a flap 9 which may be bent along the line 10 away

from the face 11 of the support. The edges 7 and 8 form three sides of a frame behind which the picture 4 is supported. 55

The fourth side of the frame is formed by the bottom edge 12 of the picture 4 which rests upon the lower bent edge 10 of flap 9. As will be seen from Fig. 1, this gives the effect of the picture lying wholly behind a cut-out picture frame, whereas in reality one edge of the picture lies on top of the material 11 and the remaining three edges lie behind the same sheet of material. 60

I prefer to employ a border to increase this effect, such a border being shown at 13 in Fig. 1. In Fig. 4 a border 14 is provided and the cuts 7 and 8 may be made through the border 14 previously printed on the support together with any other desirable decorative design. 65

As best shown in Figs. 2 and 3 the picture 4 is placed in the support by resting the bottom edge 12 of the picture upon the bent portion 10 of flap 9. In order to hold the flap 9 in the desired position a second flap 15 is formed by a three-sided cut 16 made in flap 9. Flap 15 may be bent along the line 17 and is preferably provided with an adhesive area 18 which may be pasted against the back 19 of the support, thus the upper edge of flap 9 is held toward the back face 19 of the support 1 and the picture 4 is tightly pressed forwardly against the frame. 75

Picture supports made as above described are particularly suitable for small sized "penny pictures" although, of course, the support may be made for pictures of any dimensions. Ordinarily I prefer to make the picture supports in the form shown in Fig. 4 where the flaps 9 and 15 have been cut but have not been bent from the material 11, and to ship them in this condition. Then 80 all the user has to do is press out flaps 9 and 15 and bend flaps 2 along the lines 3, and the picture holder is ready for use. 85

When it is desired to change the picture 4 it may be slid from behind flaps 9 and 15 by 100 a sideways movement in either of the directions shown by the arrows in Fig. 3. If desired the flap 15 may be opened and re-glued to the back 20 when pictures are changed. 105

After a picture has been placed in posi-

tion the flaps 2 may be folded across the face of the picture like an ordinary picture folder. They may then be bent back into the position shown in Fig. 1 to form an easel 5 when desired.

Having thus described my invention, what I claim as new and desire to secure by Letters Patent is:

1. A picture holding device including a 10 supporting member of sheet material, two flaps formed of the sheet material one flap being formed in the sheet material used for the other flap, the opening formed by bending a flap from the support constituting a 15 picture opening, one flap being adapted to support a picture in the opening and the other flap being adapted to hold the first flap to the support.
2. A picture holding device including a 20 sheet material supporting member, means for carrying and framing a picture thereon comprising a flap cut and bent from the support having a three-sided frame behind which a picture may be supported on the 25 flap, the bottom of the picture lying between the support and the flap and defining the fourth side of the frame and a connecting member between said flap and said support

for holding said flap and picture toward the support.

3. A picture holding device including a support of sheet material, a picture holding structure therefor including two flaps struck from the sheet material and adapted to be concealed by a picture located on one flap 35 behind the opening in the support left by bending the flap therefrom, the second flap being adapted to position the first flap with respect to the support.

4. A picture holding device comprising a 40 front member, a flap attached to one edge of the front member adapted to be bent to support the front member, a three sided frame formed in the front member by three intersecting cuts, a flap included between the cuts, 45 said flap being adapted to support a picture behind the frame, a second flap formed on the first mentioned flap, said second mentioned flap being adapted to be pasted against the back of the front member, 5 whereby the two flaps and picture may be held in a fixed position relative to the front member.

Signed at Chicago, Illinois, this 12th day of January, 1927.

JOHN M. BLYTH
